UNITED STATES PATENT OFFICE.

ROBERT R. LEEDS, OF ASHLAND, OHIO, ASSIGNOR TO THE TOPPING MANUFACTURING CO., OF ASHLAND, OHIO, A CORPORATION OF OHIO.

CARRIER FOR DISAPPEARING DOORS.

Application filed December 8, 1921. Serial No. 520,938.

To all whom it may concern:

Be it known that I, ROBERT R. LEEDS, a citizen of the United States of America, residing at Ashland, Ashland County, Ohio, have invented a new and useful Carrier for Disappearing Doors, of which the following is a specification.

My invention relates to a carrier for disappearing doors, and is especially useful in 10 wardrobes and the like.

The usual type of vertical disappearing door has pivots or rollers attached to the upper and lower edges, which move in suitable guides carried by the cabinet. Such 15 doors may be swung to open position and then slid backwardly into the cabinet to disappearing position. Doors as so constructed often fail to slide properly and stick, and such doors are likely to sag at the end.

20 It is the general object of my invention to provide a novel carrier for disappearing doors which will operate smoothly and with but little friction.

It is a more specific object to provide a 25 carrier which extends the full height of the door, and in which the carrier itself is mounted for sliding independently of the door.

It is a further object to provide a carrier 30 which may be adjusted to doors of various sizes.

It is still another object to provide novel means for limiting the swing of a disappearing door in one direction.

35 Other and minor objects will be apparent as the specification proceeds.

The above objects may be attained by the 40 embodiments of my invention shown in the illustrative drawings accompanying and forming part of this application.

In the drawings—

Figure 1 is a partially diagrammatic view 45 of a pair of disappearing doors for a cabinet;

Fig. 2 is a view in elevation of a disappearing door when in position to be moved to the inward position, parts being broken away and parts being shown in section;

Fig. 3 is a fragmentary view of a detail; 50 Fig. 4 is an enlarged view taken substantially in the plane of the line 4—4 of Fig. 1, parts being broken away; and

Fig. 5 is a fragmentary detail view of a modification.

Fig. 6 is a fragmentary detail showing 55 two doors and a mullion carried by a single hanger.

In said drawings, 6, 7 indicate a pair of disappearing doors. As is well known to those skilled in the art, such doors may be 60 swung to the open position and then slid inwardly so as to not obstruct the passage in front of the cabinet. A hanger bar or carriage 8 is provided for each door. This hanger bar 8 preferably extends the full 65 height of the door, and is itself mounted for sliding in the cabinet independently of any connections to the door.

One end of the hanger bar, in the instance 70 shown the lower end, is provided with a truck, which is adapted to slide along or carry the hanger bar on a suitable track 9. In the form shown, the truck includes pairs 75 of rollers 10, 11, pivoted at 12 and 13 to the cross piece or beam 14, which is secured to the lower end of the hanger bar 8. As will 80 be seen, these rollers co-operate with one side of the track 9 and are spaced apart from each other and are on opposite sides of the hanger bar. Other rollers 15 cooperate with the opposite side of the track 9. These rollers 85 are pivoted at 17 on a cantilever or beam 16 secured to and projecting laterally from the hanger bar 8. In the present disclosure the rollers 15 are spaced from the hanger 90 bar a distance different from the spacing of the other rollers, and, as shown in Fig. 4, the rollers 15 extend beyond the rollers 11. This, as will be later explained, ensures smooth action and tends to prevent the door from sagging.

In the form shown, the track 9 is mounted 95 in the lower portion of a cabinet, and the track preferably extends up to the plinth 18, and a space is provided beneath the sill 19 for accommodation of the rollers 15.

The other end of the hanger bar 8, in this 100 case the upper end, is guided by means of a stem 20, slidably mounted in the bracket or track member 21 carried by an upper portion of the cabinet. In the form shown spaced rollers 22, 23 are attached to the stem 20 and roll on suitable tracks 24, 24. In the present instance, the weight of the door is at least partially sustained by the upper 105 guide and carrier. If desired, the stem 20 may be adjustable relatively to the hanger bar 8, to compensate for slight variations in

construction and to compensate for wear. In the form shown nuts 25 secure the stem 20 to the hanger bar.

It will be seen that in the construction 5 as thus far described the carrier is in itself a complete unit and may slide to disappearing position independently of any door connection.

The door 7 is pivotally connected to the 10 hanger bar 8. In the instance shown brackets 26, 27 are attached to the hanger bar and the door is pivotally connected to said brackets, as by means of pivot pins 28, 29. If desired, one or both of these brackets 15 may be adjusting up and down relatively to said hanger bar, and for this purpose I have indicated a series of apertures 30 for receiving the elements holding the brackets to the hanger bar.

20 When the door is swung outwardly it is desirable that it be stopped in proper position so as to be slid back to disappearing position without unduly contacting with the other parts of the cabinet. Means to 25 limit the swing of the door in one or both directions are provided. In the present instance plates 31 (which may constitute hinge plates) are carried by the door and have abutment surfaces 32 thereon. The 30 brackets 26, 27 shown in dotted lines in Fig. 3 carry pins 33 for co-action with the abutments 32. The hanger bar being limited in its movement to a forward and back sliding motion, it will be obvious that, when 35 the door is opened, its limit of swing will be determined by the stop means 32, 33. If desired, the door may be provided with a second abutment 34, for contacting with the pin 33 to limit the extent of swing of the door in the other direction. It will be 40 obvious, however, that suitable jambs are preferably provided for limiting the swing of the door into the closed-door position. In 45 the form shown, similar stop means are also provided for the lower end of the door.

In Fig. 5 I have shown the two pairs of rollers 10, 11 of the lower truck as positioned above the track 9, whereas the rollers 15' are positioned below the track. In Fig. 5 the rollers 15' are also spaced a distance from the hanger bar different from that of the other rollers, but in the present modification it is spaced nearer to the hanger than either of the others. In that 50 form it will be obvious that the hanger will be prevented from tilting in either forward or backward direction, whereas, in the form shown in Fig. 4, were it not for the upper guide and carrier for the hanger, the latter 55 would be permitted to tilt in the backward direction.

In Fig. 6 has been disclosed a slight modification in which two doors 7', 7' and a mullion 35 are carried by a single hanger bar 8. The mullion may be secured to a bracket

such as 26' and the doors may be pivotally connected thereto as at 29', 29'. Suitable stops may be provided for limiting the swing of one or both doors in one or both directions, the operation being substantially 70 the same as in the case of one door heretofore described.

The operation is as follows:

When it is desired to open the door and slide it to disappearing position, the door 75 is swung outwardly in the usual manner until it is substantially parallel with the track members carried by the cabinet. If the co-operating stops means to limit the swing of the door in its outward direction 80 are provided, the door is swung as far as permitted by said stop means. The door is then pushed so as to cause the entire carrier to be slid inwardly, and the door is, of course, carried inwardly along therewith. 85 The full-line position of the parts in Fig. 4 shows the door in closed position, while the dotted line position of the parts shows the door after the same has been swung to open position and slid back into disappearing 90 position.

It will be seen that the rollers 15 not only serve to support at least a part of the weight of the door and carrier, but the rollers 15 and 10 act to prevent the door 95 from sagging. In some instances it may not be necessary to provide the upper hanger carriage, since the lower truck will properly support the parts. It is, however, desirable to have at least a guide for both the upper 100 and the lower sides of the door.

It will thus be seen that I have provided a carrier for disappearing doors which is simple and effective for the purpose intended. The carrier may be used for doors and 105 door openings of various sizes, and the operation will be smooth. The doors are not likely to stick or jam, and sagging is prevented.

While I have described in great detail forms in which my invention may be embodied, I wish it understood that some features of the invention may be used in connections other than those shown, and that various changes may be made within the scope of the invention as defined in the appended claims.

I claim:

1. In a carrier for disappearing doors and in combination with a cabinet, a hanger bar, a pair of brackets on said hanger bar, a door pivotally connected to said brackets, an upper guide and carrier for said hanger bar, a lower truck for said hanger bar, and a track for co-operation with said lower truck, 110 said lower truck including a pair of rollers on pivots spaced from said hanger bar and located respectively at the front and rear sides of said bar, said rollers co-operating with one side of said track and another roller 115

120

125

130

co-operating with the other side of said track and spaced from one of said sides of said hanger bar, said pivoted door and brackets having co-operating stop means for 5 limiting the swing of the door in one direction.

2. In a carrier for disappearing doors, a hanger bar, a door pivotally connected to said hanger bar, means for guiding one end 10 of said hanger bar, a truck for the other end of said hanger bar and co-operating with a track, said truck including a pair of spaced rollers pivotally mounted on said hanger bar and on opposite front and rear sides 15 thereof and co-operating with one side of said track to sustain vertical load, and another roller pivotally mounted on said hanger bar and spaced a different distance from the latter, said last mentioned roller 20 being on the side of the track opposite to said first-mentioned rollers.

3. In a carrier for disappearing doors, a hanger bar for pivotally supporting a door, means for guiding one end of said bar, a 25 truck for the other end of said bar and adapted to co-operate with a track, said truck including a pair of spaced rollers pivotally mounted on opposite front and rear sides of the bar and adapted to co-operate 30 with one side of a track for sustaining vertical load, and another roller pivotally mounted on said hanger bar and adapted to co-operate with the opposite side of said track, said last-mentioned roller being spaced from the 35 hanger bar a distance different from the spacing of one of the rollers on the other side of the track.

4. In a carrier for disappearing doors, a hanger bar for pivotally supporting a 40 disappearing door, a track, a truck for one end of said hanger bar and including a pair of rollers pivotally connected to said hanger bar and on opposite front and rear sides thereof, said rollers co-operating with one side of 45 said track for sustaining vertical load, and another roller pivotally connected to said hanger bar and co-acting with the opposite side of said track, and means for guiding the end of said hanger bar opposite said 50 first-mentioned end.

5. In a carrier for disappearing doors, a hanger bar, means for slidably supporting the latter, a door pivotally connected to said hanger bar, and co-acting stop means carried by said door and hanger bar for determining the limit of swing of said door in one direction.

6. In a carrier for disappearing doors, a hanger bar adapted to be slidably supported, 60 a pair of brackets carried by said hanger bar, and a door pivotally connected to said brackets, one of said last mentioned mem-

bers having a projection thereon and the other of said last mentioned members having a co-acting abutment for co-operation with said projection for determining the limit of swing of said door in one direction. 65

7. In a carrier for disappearing doors, a hanger bar adapted to be slidably supported, a bracket adjustably mounted on said hanger 70 bar, a disappearing door pivotally connected to said bracket, and co-acting stop means on said door and bracket for determining the limit of swing of said door in one direction. 75

8. As an article of manufacture, a carrier for disappearing doors, including a hanger bar for pivotally supporting a door, a truck for one end of said hanger bar, including a pair of rollers on pivots on opposite front and rear sides of said hanger bar and adapted to run on one horizontal side of a track, and a third roller on a pivot on said hanger 80 bar and spaced from each of said other rollers and adapted to run on the opposite side of the track. 85

9. In a carrier for disappearing doors, a hanger bar adapted to be slidably supported, a door pivotally connected to said hanger bar, and coacting stop means on said door and hanger bar for limiting the swing of 90 said door in the outward direction.

10. In a carrier for disappearing doors, a hanger bar adapted to be slidably supported in a cabinet, a bracket on said hanger bar, a door hinge pivotally mounted on said bracket, a projection on said bracket, said door hinge having an abutment surface for coaction with said projection for limiting the swing of said door hinge in the outward 95 direction. 100

11. In a carrier for disappearing doors, a hanger bar for pivotally supporting a door, means for guiding one end of said bar, a 105 track, a truck for the other end of said bar and including a roller at the front of and spaced from said bar and cooperating with one side of said track, and a second roller at the rear of and spaced from said bar and cooperating with the other side of said track, said rollers having bearing surfaces on horizontal portions of said track for sustaining 110 vertical loads.

12. In a carrier for disappearing doors, a hanger bar for pivotally supporting a door, means for guiding one end of said bar, a truck for the other end of said bar and adapted to cooperate with a track, said truck having spaced apart bearing surfaces at opposite front and rear sides of said bar for cooperation with one side of said track for sustaining vertical load and another bearing surface for cooperation with the other side of said track. 115 120

ROBERT R. LEEDS.
